UNITED STATES PATENT OFFICE.

VERNON C. TASKER, OF WASHINGTON, DISTRICT OF COLUMBIA, ASSIGNOR
TO AMERICAN ORDNANCE COMPANY, OF NORFOLK, VIRGINIA, A COR-
PORATION OF VIRGINIA.

AUXILIARY BARREL FOR BREECH-LOADING GUNS.

SPECIFICATION forming part of Letters Patent No. 741,079, dated October 13, 1903.

Application filed February 21, 1903. Serial No. 144,435. (No model.)

To all whom it may concern:

Be it known that I, VERNON C. TASKER, a citizen of the United States, residing at Washington, District of Columbia, have invented 5 certain new and useful Improvements in Auxiliary Barrels for Breech-Loading Guns; and I do hereby declare the following to be a full, clear, and exact description of the invention, such as will enable others skilled in the art to 10 to which it appertains to make and use the same.

This invention relates to auxiliary barrels for breech-loading guns, or, as they are usually termed, "subcaliber devices;" and it consists in the construction hereinafter pointed 15 out.

In the annexed drawings, Figure 1 represents in section and side elevation a portion of a gun and the device within the gun; Fig. 1^a, an enlarged detail, partly in section and 20 partly in elevation, of the rear adapter and auxiliary barrel applied to a gun; Fig 1^b, an enlarged section of the breech-hoop, showing a modification; Fig. 2, an enlarged section of the breech-hoop; Figs. 3 and 4, end and sec- 25 tional views of the adapter-ring; Fig. 5, the adapter-screw; Figs. 6, 7, and 8, end, sec- tional, and partial detail of the adapter-sleeve.

In the drawings the letter A indicates the 30 auxiliary barrel or subcaliber-gun, which may be built up in the usual way, consisting of the tube a, the jacket a', and the breech-hoop B. This barrel A is provided on its exterior surface with two sets of screw-threads a² a³ 35 of the same pitch and direction, one set, a², being near the muzzle a⁴ and the other set, a³, being about the middle a⁵ of the subcaliber- gun. Engaging the front threads a³ is a front adapter C, which fits on its outer rim c the 40 bore of the large or main gun. Engaging the threads a² is the middle adapter D, on its outer rim d fitting the bore of the large gun, preferably where the taper of the bore stops. The rear end of the tube a has the usual 45 breech-hoop B, upon which is placed a steel ring E. This ring is provided with a number of threaded holes e and at one side with a screw-seat e'. This screw-seat e' runs obliquely from one face e² of the ring outwardly 50 to the outer periphery of the ring and has a threaded portion e³ at the face e² and a smooth portion e⁴. At the inner and upper end e⁵ of

the smooth portion e⁴ of the seat e' there is a slit or opening e⁶ in the outer periphery of the ring E. Upon this ring E is placed a 55 brass sleeve F, held thereto by pins f, engag- 60 ing the holes e, and having a tongue f', formed by making slits f² in the sleeve, such tongue coming over the slit or opening e⁶ in the ring E. Seated in the seat e' of the ring E is a 65 screw G, having the threads g, which engage the threads e³ of the seat e', and a smooth por- 70 tion g', which is within the smooth portion e⁴ of this seat, the point g² of the screw passing through the slit or opening e⁶ and pressing 75 against the tongue f' of the sleeve F.

The subcaliber-gun with the several adap- 75 ters are put in position as shown in Fig. 1. After they are duly placed and adjusted by turning the barrel within the adapters the 80 screw G is turned inwardly, forcing the point g² thereof through the slit or opening e⁶ against the tongue f' of the sleeve F and binding the tongue against the inner face or bore of the 85 large or main gun, thus firmly holding the 90 subcaliber-gun in place.

In Fig. 1^b is shown a modification. The ring E is dispensed with, and the oblique seat is made in the breech-hoop, the screw pass- 95 ing through the breech-hoop and the brass sleeve being secured thereon without the intervention of the ring E.

Having thus described my invention, what I claim is—

1. The adapter for a subcaliber-gun, con- 85 sisting of a main portion having an oblique screw-seat provided with an opening at the edge of such main portion, a screw in said seat, the inner end of the screw being at such opening, and a sleeve outside of the main por- 90 tion having a flexible part where the end of the screw comes to the opening.

2. The combination of the ring, E, having the oblique screw-seat, e', and the opening, e⁶; the screw, G, fitting in such screw-seat 95 and having its end, g², at the opening, e⁶; and the sleeve, F, having the tongue, f, located at the opening, e⁶.

In testimony whereof I affix my signature in presence of two witnesses.

VERNON C. TASKER.
